CARTON WITH AUTOMATIC COVER
LOCKING MEANSWalter C. George, St. Louis, Mo., assignor to Gay-
lord Container Corporation, St. Louis, Mo., a
corporation of Maryland

Application November 1, 1948, Serial No. 57,807

8 Claims. (Cl. 229—45)

1
This invention relates principally to cartons of the kind having slip or hinged covers. It has for its principal objects to provide readily releasable means for automatically locking the cover of the carton in closed position, to provide for quickly and firmly securing the locking elements to the body and cover of the carton, to provide for automatically locking the cover in different closed positions, to utilize the locking elements of the cover and/or body for securing a folded flap thereof, and to provide for simplicity and cheapness of construction of the locking elements.

The invention consists in a carton having a cover locking means comprising two locking elements secured one to the body of the carton and the other to the cover thereof for automatic interlocking engagement in the closed position of the cover and for quick manual disengagement in such position. It also consists in providing the locking elements with means for firmly securing them to the body and cover, respectively. It also consists in adapting the locking elements for locking the cover in different closed positions. It also consists in utilizing the locking element of the body or cover as a securing means for a folded-over flap portion thereof. The invention also consists in the parts and combinations and arrangements of parts hereinafter described and claimed.

In the accompanying drawing, wherein like symbols refer to like parts wherever they occur,

Fig. 1 is a perspective view of a carton provided with a cover locking device embodying my invention, the cover being shown detached from the body of the carton.

Fig. 2 is a fragmentary vertical sectional view on the line 2—2 in Fig. 3.

Fig. 3 is an enlarged vertical sectional view on the line 3—3 in Fig. 2, the cover being shown in fully telescoped position.

Fig. 4 is a view similar to Fig. 3, the cover being shown in partially telescoped position.

Fig. 5 is a perspective view looking at one side of the locking member.

Fig. 6 is a perspective view looking at the opposite side of said locking member.

Fig. 7 is a view similar to Fig. 3, showing a modified form of cover locking device; and

Fig. 8 is a perspective view of the locking member carried by the cover shown in Fig. 7.

In the accompanying drawing, my invention is shown embodied in a carton of resilient material comprising a body A and a slip cover B therefor. The body A has two opposite side walls 1 with

5 upper marginal flaps 2 that are folded downwardly against the outer side faces of said walls and secured flatwise thereto by staples 3 or other suitable fastening means. The slip cover B comprises a top panel 4 with two depending opposite side flanges 5 that overhang the opposite side walls 1 of the body A in spaced relation thereto and have lower marginal flaps 6 that are folded upwardly flatwise against the inner faces of said 10 cover flanges and are held in place by lugs 7 that project upwardly from the upper edges of said flaps and fit in vertical openings 8 provided therefor in the top panel 4 of said cover. In the fully closed position of the slip cover B, the top panel 15 4 thereof seats on the top edges of the side walls 1 of the body B and the depending side flanges 5 of said cover extend downwardly outside said walls to about the level of the lower edges of the downturned upper marginal flaps 2 thereof.

20 The carton is provided between at least one side wall 1 and the cover flange 5 associated therewith with means for automatically locking the cover B to the body A in fully telescoped position or in any one of a plurality of partially telescoped positions. This cover locking means preferably comprises two counterpart locking members C of molded plastic or other relatively rigid and durable material secured one to the depending cover flange 5 and the other to the body side wall 1 overlapped thereby. Each of the locking members C comprises a flat rectangular plate-like base portion 9 with outstanding transverse flanges 10 projecting from one face thereof substantially at right angles thereto. The drive flanges 10 are preferably located at the ends of 25 the body portion 9 and extend from side to side thereof and are thickened out on opposite sides at their outer side margins to form ribs 11 and rearwardly facing square shoulders 12 on opposite sides of said flanges at the rear edges of said ribs. As shown in the drawings, the thick outer marginal ribs 11 of the flanges 10 extend from end to end thereof and are tapered from the shoulders 12 to their outer edges after the manner of a wedge.

30 Projecting from the opposite face of the plate-like base portion 9 of each locking member C is a series or row of equally spaced teeth or ribs 13 that extend transversely of said base portion from side edge to side edge thereof with one tooth located at each end thereof. The teeth 13 all slant or incline towards one end of the base portion 9 at the same oblique angle and taper correspondingly in thickness from said base portion to

their outer edges where they are rounded, as at 14, throughout their length.

One of the two locking members C is mounted on the outer face of each of the side walls 1 of the body A near the upper edge of said wall midway of the length thereof with the teeth 13 disposed one above another and inclining downwardly and outwardly relative to said wall. The other locking member C of the two part fastener is mounted on the inner face of the depending cover flange 5 midway of the length and depth thereof and is turned end for end relative to the locking member on the body A so that the teeth 13 of said other member incline inwardly and upwardly. The teeth of the two locking members are disposed in vertical alinement when the cover is applied and the taper of the teeth is such that the top and bottom faces of each member slope in conformity with the bottom and top faces, respectively, of the other member.

The locking member of the body A is secured thereto by driving the flanges 10 through the downturned upper marginal flap 2 of the side wall 1 of said body until the wedge shaped marginal rib 11 of said flange passes entirely through the said flap and imbeds itself in said wall, the shoulders snap behind said flap, thereby preventing extraction of said flanges and firmly securing said locking member to said body. The other locking member C is firmly secured in a similar manner to the upturned lower marginal flap 8 of the depending flange 5 of the cover B.

In the modified construction shown in Figs. 7 and 8, the side wall 1 of the body A of the carton has its upper marginal flap 2 turned down flatwise against the inner face of said wall and one of the locking members C is mounted on said wall in the position hereinbefore described with its anchor flanges 10 extending through both the walls and flap so as to rigidly secure said member to said wall and also hold said flap in place. In this modified construction, the locking lugs 7 on the upturned lower marginal flap 8 of the depending cover flange 5 are dispensed with and the anchor flanges 10 of the locking member C¹ mounted on said wall extend through said wall and flap to hold the latter in place. In this construction the locking member C¹ is provided with one tooth 13 only.

By the arrangement described, the slip cover may be quickly and easily locked in position on the body of the carton by telescoping said cover downwardly over said body far enough to cause the inwardly and upwardly inclined teeth of the locking members carried by the cover flanges to ride over the downwardly and outwardly inclined teeth of the locking members mounted on the side walls of the body and snap into position beneath said last mentioned teeth, thereby preventing disengagement of the cover by a straight upward pull or lift thereon. During the downward movement of the cover, the flexibility of the flanges thereof permits said flanges to spring outwardly far enough to enable the teeth of the locking member carried by the cover to ride over and snap beneath the teeth of the locking member mounted on the side wall of the body. When it is desired to remove the cover, the flanges thereof are pulled outwardly far enough from the walls of the body to disengage the teeth of the locking member carried by the cover from the teeth of the locking member mounted on the body, thereby permitting the cover to be lifted off the body. During the closing movement of the cover, the teeth of the locking member there-

of ride flatwise on the teeth of the locking member of the body. When the cover is closed, the teeth of the two locking members also bear flatwise on one another. The teeth of the locking member carried by the cover may be engaged with any one of the teeth of the locking member mounted on the body, depending upon the amount of overlap between the cover flanges and the body walls. This arrangement permits the cover to be locked in fully or partially telescoped position and it is especially advantageous with fruit and produce cartons wherein the contents initially extend above the top of the body but shrinks or settles during shipment.

The optimum angle of the engaging faces of the interlocked ribs 13 is 50 degrees and the optimum angle of the opposite faces of said ribs is 65 degrees. These angles insure easy sliding movement of the ribs one over another and permit the locking members to be readily disengaged by pressing the wall of the body inwardly or by pulling the rim of the cover outwardly; and these angles also provide a toe-in effect of the engaged cover and body ribs which has a tendency to cause the engaged ribs to become more fully engaged regardless of the vertical load on the cover. However, satisfactory performance may be obtained with angles varying considerably from the optimum; the preferred ranges of angles being between 40 and 60 degrees for the engaged sides of the interlocked ribs and between 55 and 75 degrees for the opposite sides thereof.

What I claim is:

1. A carton of resilient material comprising a body having a side wall and a cover having a depending flange adapted to overhang said wall in spaced relation thereto, and a locking device for said cover comprising a locking member mounted on the outer face of said wall and having a rigid rib inclining downwardly and outwardly therefrom and a locking member mounted on the inner face of the depending cover flange and having a rigid rib inclining inwardly and upwardly therefrom and adapted during the closing movement of said cover to slide downwardly and outwardly over said first mentioned rib and snap beneath the latter and to be disengaged therefrom by an outward pull on said depending cover flange, said locking members having a flange projecting therefrom that has a thickened wedge shaped outer marginal rib adapted to be driven through said body wall or cover flange and seat against the inner face thereof to thereby secure the locking member thereto.

2. A carton of resilient material comprising a body having a side wall and a cover having a depending flange adapted to overhang said wall in spaced relation thereto, and a locking device for said cover comprising a locking member mounted on the outer face of said wall and having a plurality of vertically spaced rigid ribs inclining downwardly and outwardly therefrom and a locking member mounted on the inner face of the depending cover flange and having a single rigid rib inclining inwardly and upwardly therefrom and adapted during the closing movement of said cover to slide downwardly and outwardly over any one of said first mentioned ribs and snap beneath the latter and to be disengaged therefrom by an outward pull on said depending cover flange, said locking members having a flange projecting therefrom that has a thickened wedge shaped outer marginal rib adapted to be driven through said body wall or cover flange

and seat against the inner face thereof to thereby secure the locking member thereto.

3. The combination set forth in claim 2 wherein in the outer edges of said ribs are rounded and said ribs taper in thickness from their base portions to their rounded outer edges and the top and bottom faces of said single rib are disposed at angles corresponding to the bottom and top faces, respectively, of said plurality of ribs.

4. A carton of resilient material comprising a body having a folded side wall and a cover having a folded depending flange adapted to overhang said wall in spaced relation thereto and a locking device for said cover comprising a locking member mounted on the outer face of said wall and having a rigid rib inclining downwardly and outwardly therefrom and a locking member mounted on the inner face of the depending cover flange and having a rigid rib inclining inwardly and upwardly therefrom and adapted during the closing movement of said cover to slide downwardly and outwardly over said first mentioned rib and snapped beneath the latter and to be disengaged from said first mentioned rib by an outward pull on said depending cover flange, each of said locking members having a flange projecting therefrom that has a thickened wedge shaped outer marginal rib adapted to be driven entirely through said folded wall or cover flange to hold the folds thereof together and the locking member in place.

5. A carton of resilient material comprising a body having a side wall and a cover having a depending flange adapted to overhang said wall in spaced relation thereto, and a locking device for said cover comprising a locking member mounted on the outer face of said wall and having a rigid rib inclining downwardly and outwardly therefrom and a locking member mounted on the inner face of the depending cover flange and having a rigid rib inclining inwardly and upwardly therefrom and adapted during the closing movement of said cover to slide downwardly and outwardly over said first mentioned rib and snap beneath the latter and to be disengaged therefrom by an outward pull on said depending cover flange, each of said locking members having a flange projecting therefrom that has a wedge shaped outer marginal portion adapted to be driven into said body wall or cover flange to secure the locking member thereto.

6. A carton of resilient material comprising a body having a side wall and a cover having a depending flange adapted to overhang said wall in spaced relation thereto, and a locking device for said cover comprising a locking member mounted on the outer face of said wall and having a plurality of vertical spaced rigid ribs inclining downwardly and outwardly therefrom and a locking member mounted on the inner face of

the depending cover flange and having a single rigid rib inclining inwardly and upwardly therefrom and adapted during the closing movement of said cover to slide downwardly and outwardly over any one of said first mentioned ribs and snap beneath the latter and to be disengaged therefrom by an outward pull on said depending cover flange, each of said locking members having a flange projecting therefrom that has a wedge shaped outer marginal portion adapted to be driven into said body wall or cover flange to thereby secure the locking member thereto.

7. A carton of resilient material comprising a body having a side wall and a cover having a depending flange adapted to overhang said wall in spaced relation thereto, and a locking device for said cover comprising two counterpart locking members each having a series of spaced outstanding teeth on one face thereof all slanting in the same direction, one of said locking members being mounted on the outer face of said wall with its teeth inclining downwardly and outwardly therefrom and the other of said locking members being mounted on the inner face of the depending cover flange with its teeth inclining inwardly and upwardly therefrom and adapted during the closing movement of said cover to slide downwardly and outwardly over and snap beneath the teeth of said first mentioned locking member and to be disengaged therefrom by an outward pull on said depending cover flange, each of said locking members having a flange projecting therefrom that has a thickened wedge shaped outer marginal web adapted to be driven through said body wall or cover flange and seat against the inner face thereof to thereby secure the locking member thereto.

8. The combination set forth in claim 7 wherein the outer edges of the teeth of each of said locking members are rounded and said ribs taper in thickness from their base portions to their rounded outer edges and the top and bottom faces of the downwardly inclined teeth are disposed at angles corresponding to the bottom and top faces, respectively, of the upwardly inclined teeth.
